UNITED STATES PATENT OFFICE.

FRANK SLOGR, OF OMAHA, NEBRASKA.

ROLLER SKATE.

Application filed April 10, 1924, Serial No. 705,543. Renewed May 20, 1925.

To all whom it may concern:

Be it known that I, FRANK SLOGR, a citizen of the United States of America, residing at Omaha, in the county of Douglas and State of Nebraska, have invented certain new and useful Improvements in Roller Skates, of which the following is a specification.

This invention relates to certain new and useful improvements in roller skates and has particular reference to a skate of the two-wheeled type and the manner of supporting the wheels upon the skate frame.

The primary object of the invention is to provide a roller skate wherein a skate frame embodying extensibly connected sole and heel plates carries depending resilient bracket arms fashioned at their lower ends for rotatably supporting a cross shaft upon which a single roller is journaled to be retained in position in the absence of the usual nut and screw connections.

With the above general objects in view and others that will appear as the nature 25 of the invention is better understood, the same consists of the novel form, combination and arrangement of parts hereinafter more fully described, shown in the accompanying drawing and claimed.

30 In the drawing, wherein like reference characters designate corresponding parts throughout the several views,

Figure 1 is a side elevational view of a roller skate constructed in accordance with the present invention,

Figure 2 is a top plan view of the same,

Figure 3 is a vertical cross-sectional view taken on line III—III of Fig. 1,

Figure 4 is a vertical cross-sectional view 40 taken on line IV—IV of Fig. 1,

Figure 5 is a perspective view of one of the bracket mountings for the wheel or roller,

Figure 6 is a developed plan view of the 45 bracket, and

Figure 7 shows edge elevational view of the form of bracket shown in Fig. 6.

The roller skate embodies a frame structure having sole and heel plates 1 and 2 respectively connected together by cooperating adjustable extensions 3, the sole plate 1 carrying the usual sole engaging screw adjustable clamps 4 while the heel plate 2 carries the heel engaging flange 5 to which heel straps may be attached in the usual manner.

Single rollers 6 are positioned beneath the sole and heel plates 1 and 2 respectively, the mounting or bearing for each roller 6 embodying a pair of resilient brackets depending from the sole and heel plates to support the roller in the absence of the usual nuts and screws. The manner of constructing one of the brackets for supporting a roller is disclosed in Figs. 6 and 7, the arm 65 7 carrying a mounting plate 8 at one end thereof that is adapted to be angularly bent as shown in Fig. 5 and provided with a series of openings 8^a to accommodate riveting the bracket arm 7 as at 9 to the sole and 70 heel plates 1 and 2. The lower depending end of the bracket arm 7 carries a cross head 10 substantially rectangular in plan view with a grooved or ribbed portion 11 extending longitudinally of the cross head 75 10 while diametrically opposite corners of the cross heads carry relatively long finger extensions 12 and 13 disposed at opposite sides of the groove 11. The lower end of the arm 7 adjacent the cross head 10 is provided 80 with an opening 14 for purposes presently to appear.

The arm 7 is bent upon a transverse line slightly below the opening 14 in a direction opposite the bracket mounting 8 and the 85 cross head 10 is then bent into circular formation to form an annular groove or channel in the circularly bent cross head as shown in Figs. 3 and 4. The finger extensions 12 and 13 are then bent into circular formation, 90 the finger 12 overlapping the opposite side of the cross head 10 while the finger 13 is positioned between the grooves 11 and the bracket arm 7.

The roller 6 includes a supporting frame 95 15 having a central tubular web or bearing 16 that encloses a shaft 17 having flanges 18 upon opposite ends thereof. The flanges 18 are received in the annular grooves 11 and the free ends of the circular portions of the cross head engage the shaft inwardly of the flanges and abut the opposite ends of the wheel bearing 16 as shown in Fig. 4. The split bearings for the ends of the shaft 105 17 are resilient so that the rollers may be mounted upon the bracket arms by forcibly separating or expanding the bearings at the lower ends of the bracket arms 7. It will be noted that the openings 14 appear at the outer sides of the bracket arms, and upon 110 bending the cross head 10 into circular formation, the walls of the openings are slightly

distorted to form a lip at the lower side of the opening forming a retaining wall for a lubricant that is introduced at the ends of the bearings for the roller.

5. The cooperating bracket arms may be forcibly separated for removing a roller and shaft carried thereby.

While there is herein shown and described the preferred embodiment of the present 10 invention, it is nevertheless to be understood that minor changes may be made therein without departing from the spirit and scope of the invention as claimed.

What is claimed as new is:—

15. 1. In a roller skate, extensibly connected sole and heel plates, bracket arms depending from the plates, each arm being struck from sheet metal and bent to provide a circular bearing at its lower end with an annular groove in the bearing and a shaft carrying a roller and having an annular flange at each end received in the bearing groove.

2. In a roller skate, extensibly connected 25 sole and heel plates, bracket arms depending from the plates, each arm being struck from sheet metal and bent to provide a circular bearing at its lower end with an annular groove in the bearing, a shaft carrying a roller and having an annular flange at each end received in the bearing groove, said bearing being bent from a rectangular plate with the edges moved into abutting relation and tongue extensions carried by 30 the meeting edges of the bearing and circularly inclosing the bearing.

3. In a roller skate, extensibly connected sole and heel plates, bracket arms depending from the plates, each arm being struck 40 from sheet metal and bent to provide a circular bearing at its lower end with an annular groove in the bearing, a shaft carrying a roller and having an annular flange at each end received in the bearing groove, and said bracket having an opening therein 45 alined with the end of the shaft to facilitate lubrication of the bearing.

4. In a roller skate, extensibly connected sole and heel plates, bracket arms depending from the plates, each arm being struck 50 from sheet metal and bent to provide a circular bearing at its lower end with an annular groove in the bearing, a shaft carrying a roller and having an annular flange at each end received in the bearing groove, said bearing being bent from a rectangular plate with the edges moved into abutting relation, tongue extensions carried by the meeting edges of the bearing and circularly inclosing the bearing, and said bracket having 55 an opening therein alined with the end of the shaft to facilitate lubrication of the bearing.

5. In a roller skate, extensibly connected sole and heel plates, bracket arms depending 60 from the plates, each arm being struck from sheet metal and bent to provide a circular bearing at its lower end with an annular groove in the bearing, a shaft carrying a roller and having an annular flange at 70 each end received in the bearing groove, said bracket having an opening therein alined with the end of the shaft to facilitate lubrication of the bearing.

6. In a roller skate, extensibly connected 75 sole and heel plates, bracket arms depending from the plates, each arm being struck from sheet metal and bent to provide a circular bearing at its lower end with an annular groove in the bearing, a shaft carrying a roller and having an annular flange at each end received in the bearing groove, said bearing being bent from a rectangular plate with the edges moved into abutting relation, tongue extensions carried by 80 the meeting edges of the bearing and circularly inclosing the bearing, said bracket having an opening therein alined with the end of the shaft to facilitate lubrication of the bearing, and an upturned lip at the lower 90 side of the opening to retain the lubricant in the bearing.

In testimony whereof I affix my signature.
FRANK SLOGR.
